C. G. PALMER.

DOOR LOCK.

APPLICATION FILED MAR. 26, 1919. RENEWED MAR. 14, 1921.

1,391,005.

Patented Sept. 20, 1921.

INVENTOR
Charles G. Palmer,
By
Fred C. Fischer.
ATTORNEY

UNITED STATES PATENT OFFICE.

CHARLES G. PALMER, OF NEWARK, NEW JERSEY.

DOOR-LOCK.

1,391,005.

Specification of Letters Patent. Patented Sept. 20, 1921.

Application filed March 26, 1919, Serial No. 285,189. Renewed March 14, 1921. Serial No. 452,231.

To all whom it may concern:

Be it known that I, CHARLES G. PALMER, a citizen of the United States, residing in the city of Newark, county of Essex, and 5 State of New Jersey, have invented certain new and useful Improvements in Door-Locks, of which the following is a full, clear, and exact description, such as will enable others skilled in the art to which it 10 pertains to make, construct, and use the same, reference being had to the accompanying drawings, and to numerals of reference marked thereon, forming a part of this specification.

15 My invention relates to a door lock specially adapted to be used in connection with fire proof doors and buildings and is of the type wherein, the door automatically opens when my devices are pushed against. The 20 object of the invention is the production of a door lock, which shall be simple and effective in construction, comparatively inexpensive in cost, and provided with means whereby, in the event of a panic, heavy 25 pressure applied against the inner side of an outwardly opening door, the lock mechanism would be released by said pressure instead of by the usual turning movement practised in the case of the usual knob lock. 30 With this end in view, my invention consists in certain novelties of construction and arrangements of parts, as hereinafter set forth and pointed out in the claims.

While the preferred form of my invention 35 is illustrated in the accompanying drawings, yet it is to be understood that minor changes may be made without departing from the scope thereof.

In the accompanying drawings, 40 Figure 1 represents a vertical sectional elevation of a door provided with my improved lock, the latch bolt housing and the socket members also being shown in section.

45 Fig. 2 represents on an enlarged scale a vertical sectional elevation of the latch bolt and parts in their normal locked position.

Fig. 3 represents a similar view illustrating the parts in unlocked position.

50 Fig. 4 represents a front elevation of the latch bolt and its housing.

Fig. 5 represents a side elevation of the socket member designed to be secured to the top of the floor frame, and

55 Fig. 6 represents a transverse section of said socket member illustrating the lock

bolt and trigger in their normal locked position.

In the drawings 1 represents the door frame, and 2 the door hinged to the frame. 60 An upright rod 4 is movable vertically through a slotted housing 5 on the door. A lever 6 projects through a slot into the housing to which it is intermediately pivoted as at 7. The lever within the housing 65 is provided with a bifurcated end which straddles the rod 4, said rod being provided with a pin or stud 8 which is in engagement with said bifurcated end of the lever 6.

When the external end of the lever 6 is 70 pushed toward the door, its end within the housing lifts the rod 4, and vice versa when no one is pushing against the lever, then the weight of the rod 4 of the connected part returns the lever 6 automatically into 75 its original or normal position, as shown in Fig. 1.

The latch bolt 9 adjustably secured to the upper end of the upright rod 4, by means of a lock nut 3, is slidably located within a 80 suitable housing 10 attached to the upper part of the door. A similar housing 11 is attached to the lower part of the door, in which the other or free end of the upright rod 4 is slidably supported. The latch bolt 85 9 at its upper end, is provided with, preferably, integral lateral extensions 12 constituting the integral lock bolt of the latch bolt 9, which is receivable into a socket member 14 which is screwed to the top of the 90 door frame.

In the drawings, there are two socket members, one to receive the locking bolt located above and the other socket member 15 located below, in the floor or threshold which 95 is designed to receive the free end of the upright rod 4. The upper end of the latch bolt 9 is preferably, provided with a cavity 16, and the front face of the latch bolt with an elongated slot 17. Two diametrically opposed slots 18 are also provided in the sides of the latch bolt to receive a stud 19 which passes through said diametrically opposed slots 18, and the ends of which are secured in the housing 10, as clearly indicated in 100 105 the drawings.

A stud 20, preferably formed integral upon the rear inner face of the latch bolt, extends into the cavity 16.

Pivotedly mounted upon the stud 19 is a 110 weighted trigger 21 provided with an upper outwardly projecting extension 22 terminat-

ing in the head 23; the lower end of said trigger being provided with a hooked shaped portion 24 designed to engage with and be disengaged from the inwardly projecting 5 stud 20.

The socket member 14 which is screwed to the top of the door frame, preferably consists of a single casting comprising a supporting plate 25 from which rises a box-like 10 casing 26, provided with an open end, the central portion of said supporting plate 25 being provided with a downwardly extending lug 27, the inner surface of which is designed to be engaged by the head 23 of the 15 trigger 21, as clearly indicated in the drawings. Extending downwardly from the underside of the supporting plate 25, are two ribbed holding lugs 28—28 designed to have holding and locking engagement with the 20 two lateral extensions 12, of the lock bolt, when the parts are in the position indicated in the drawings, see Figs. 1 and 6, showing the door in locked position.

These lugs 28—28, are located on the rear 25 of the socket member and project downwardly from the supporting plate 25, as previously described, the lugs 28—28 extending toward each other near the open end of the box-like casing.

30 The operation of the illustrated device will be apparent from what has already been said; namely, that when the external end of the lever 6 is pushed toward the door, its end within the housing lifts the rod 4, and 35 the latch bolt 9, thereby disengaging the lower free end of the rod 4, from the socket member 15, located in the floor or threshold, and causes the end of the latch bolt 9 with its lock bolt to enter the box-like casing 26, at the 40 same time causing the hooked shaped portion 24 of the trigger 21 to be hooked under the underside of the stud 20 in the cavity 16 of the latch bolt 9, see Fig. 3, when the lock bolt 13 has been moved into the box-like 45 casing 26, and the lateral extensions 12 of the lock bolt will become disengaged from the holding lugs 28 of the socket member 14, and the lock bolt is therefore free to pass out through the open end of the casing 26, 50 and to be moved out of locking and holding position with the socket member 14. By closing the door, the parts are brought into locking position by means of the head 23 of the trigger engaging with the downwardly 55 extending lug 27 of the socket member 14, which causes the hooked shaped portion 24 thereof, to become disengaged from the stud 20, permitting the free end of the rod to drop into the socket member 15 in the floor, 60 and the lateral extensions 12 of the lock bolt to drop behind the lugs 28—28 of the socket member 14, as illustrated in Fig. 2 of the drawing.

65 Experience has demonstrated that the organization above described is a highly ef-

ficient one, and while I have shown the preferred embodiment of my present invention, I do not wish to be limited to the exact details of construction shown and described, as obvious modifications thereof, not involving the exercise of invention, may be made by any skilled mechanic, and such departures from what is herein set forth, I consider within the scope of terms of my claims.

Having thus described my invention, what 75 I claim as new and desire to secure by Letters Patent is:—

1. The combination with a door and its frame, a rod or bar adapted to be mounted on the door, a lever pivotally connected to said rod or bar for moving the said rod from its normal position, housings secured to the door, a bolt provided with a recess slidably arranged within one of said housings and connected with said rod at one end thereof, 80 said bolt being provided with an integral laterally arranged lock bolt, a trigger pivotally secured and located within the recess of said bolt, a socket member for the bolt provided with an open end, said socket member being provided with a downwardly extending lug to be engaged by one end of said trigger, and provided further with two downwardly extending lugs designed to 85 have holding and locking engagement with the said lock bolt, whereby the movement of the rod in one direction causes the lock bolt to become disengaged from the holding lugs to withdraw the same from said socket member.

2. The combination with a door and its frame, a rod or bar adapted to be mounted on the door, a lever pivotally connected to said rod or bar, for moving the said rod from its normal position, housings secured to the door, a bolt provided with a recess slidably arranged within one of said housings and connected with said rod at one end thereof, 100 said bolt being provided with an integral laterally arranged lock bolt, a trigger pivotally secured to and located within the recess of said bolt, and means located within the recess of said bolt for engagement with one end of said trigger for holding said bolt in unlocked position, a socket member for the bolt provided with an open end, said socket member being provided with a downwardly extending lug to be engaged by one end of said trigger, and provided further with two downwardly extending lugs designed to have holding and locking engagement with the said lock bolt, whereby the movement of the rod in one direction causes the lock bolt to become disengaged from the holding lugs to withdraw 110 the same from said socket member.

3. The combination with a door and its frame, a rod or bar adapted to be mounted on the door, a lever pivotally connected to said rod or bar, for moving the said rod 115

from its normal position, housings secured to the door, a latch bolt provided with a lock bolt arranged within one of said housings and connected with said rod at one end 5 thereof, a trigger pivotally secured to the latch bolt, a socket member for the lock bolt provided with an open end, and downwardly extending front and rear lugs, the front lug to be engaged by said trigger and the rear lugs to have holding and locking engagement with the said lock bolt, whereby the movement of the rod in one direction causes the lock bolt to become disengaged from said lugs to withdraw the same from 10 said socket member.

4. The combination with a door and its frame, a bar or rod adapted to be mounted on the door, a lever pivotally connected to said rod or bar for moving the said rod from 15 its normal position, housings secured to the door, a latch bolt slidably arranged within

one of said housings and connected with said rod at one end thereof, said latch bolt comprising a trigger pivotally connected within said latch bolt and projecting therefrom and further provided with a lock bolt at the top thereof, a socket member for the lock bolt provided with front and rear extensions, the front extension to be engaged by the projecting portion of the trigger and the rear extensions to be engaged by the lock bolt, whereby the movement of the rod in one direction causes the said lock bolt to become disengaged from said extensions to withdraw the same from said socket member. 25 30 35

This specification signed and witnessed this 22nd day of March, 1919.
